BICYCLE FRAME

Sherwood B. Ross, Woodsburgh, N.Y., assignor to Chain Bike Corporation, Rockaway Beach, N.Y., a corporation of New York

Filed May 2, 1966, Ser. No. 2,128

Term of patent 14 years

(Cl. D90—8)

I claim:

The ornamental design for a bicycle frame, substantially as shown.
